United States Patent Office.

JAMES E. McBETH, OF NEW ORLEANS, LOUISIANA.

Letters Patent No. 79,139, dated June 23, 1868.

IMPROVEMENT IN POCKET-KNIVES.

The Schedule referred to in these Letters Patent and making part of the same.

TO ALL WHOM IT MAY CONCERN:

Be it known that I, JAMES E. McBETH, of city of New Orleans, in the parish of Orleans, and in the State of Louisiana, have invented certain new and useful Improvements in Pocket-Knives; and do hereby declare that the following is a full, clear, and exact description thereof, reference being had to the accompanying drawings, and to the letters of reference marked thereon.

The nature of my invention consists in sharpening the upper part of the blade only, and providing this part with flanges or projections, one on each side, and having the blade under such flanges or projections filed away in a concave shape, the object hereof being to pare the finger-nails without cutting into the quick or the flesh of the finger; and to prevent the nervous creeping sensation consequent upon the sharp edge of a knife passing over the flesh of the finger in the paring of the nails.

To enable others skilled in the art to make and use my invention, I will proceed to describe its construction and operation.

In the annexed drawings forming part of this specification, A represents the handle of a knife, B the blade, which is constructed in the following manner: The upper part, a, thereof, only is sharpened, and provided with a small flange or projection, C, on each side of the blade, of proper size for insertion under the finger-nail while it is being pared, one flange or projection for the right hand, and the other for the left hand, to prevent the cutting into the quick, while immediately under such flanges or projections the blade is filed away in a concave formation, c, to adapt itself to the rounded shape of the end of the finger, as shown in Figure 2.

The edge of the blade thus filed away is blunt and rounded, in order to pass smoothly over the end of the finger while paring the nails. The flanges or projections C C are also rounded on the edge, and formed concave underneath, so that they will move with ease between the nail and the flesh of the finger.

The flange is inserted under the nail of the finger at the side farthest from the person, and when it has pared the nail to the other or nearest side, the flange, pressing on the flesh, will prevent the sharp edge from cutting the nail too much, and also from coming in contact with the flesh, and will cause it to pass off from the finger.

Having thus fully described my invention, what I claim as new, and desire to secure by Letters Patent, is—

The blade B, with the upper part, a, only sharpened, flanges C and concave c, arranged and operating substantially as and for the purposes herein set forth.

In testimony that I claim the foregoing, I have hereunto set my hand, this 20th day of April, 1868.

JAMES E. McBETH.
